UNITED STATES PATENT OFFICE.

ROBERT N. COOPER, OF BLOOMINGTON, ILLINOIS, ASSIGNOR TO WALTER W. WILLIAMS, OF BLOOMINGTON, ILLINOIS.

REFRIGERATING UNIT.

Application filed October 27, 1927. Serial No. 229,009.

This invention relates to improvements in domestic refrigerating plants and more particularly to the refrigerating unit placed in the refrigerating or ice chamber of a 5 domestic ice box.

It is an object of this invention to provide a refrigerating unit employed in a domestic refrigerating machine of the compression type employing the flooded system 10 with a float valve chamber for regulating the supply of the refrigerant which will be connected directly to the unit without substantially increasing the width thereof. In 15 systems of this kind employed in this type of domestic refrigerating machine, it has been customary to construct the refrigerating units in sections and it is an object of this invention to insert the float chamber between the upper connection of such sections and a spacer of equal width between 20 the lower connection of such sections, whereby the float valve chamber may be said to become an integral part of the refrigerating unit contained within the refrigerating or 25 ice chamber of the ice box.

While the preferred form of this invention is illustrated upon the accompanying sheets of drawings, it is to be understood that minor detail changes may be made 30 without departing from the scope thereof.

In the drawings:

Figure 1 is a view in perspective illustrating the preferred form of this invention.

Figure 2 is a view in vertical transverse section taken on the line 2—2 of Figure 3, 35 looking in the direction of the arrow.

Figure 3 is a view in longitudinal vertical section taken on the line 3—3 of Figure 2, looking in the direction of the arrow.

As above stated it is customary in this 40 art to construct units of this character in sections. Two of such sections, 1 and 2, are illustrated in Figure 1 connected to each other at the top and bottom by bolts 3.

Each section is hollow, as shown in Figure 45 2, the interior of which communicates with enlarged central bosses 4 at the top and bottom thereof, the adjacent or meeting edges of which are provided with a tongue and groove connection, as shown in Figure 2, and the sides of each section are provided with vertical and horizontal outstanding ribs, as shown in Figures 1 and 2. In accordance with this invention a float chamber 50 5 is provided with a depending boss 6, hav-

ing vertical faces of the same size and contour as the meeting edges of the upper bosses 4 of the sections, one face of which is provided with a tongue 7 and the opposite face with a groove 8 which boss 6 is interposed 55 between the upper bosses 4 of respective sections forming a tongue and groove connection therewith and held in gas and liquid tight contact by the bolts 3. The interior of the float chamber communicates with the 60 interior of the boss, as shown in Figure 3, and the float chamber boss communicates with the interior of the section boss 4, as shown in Figure 2. A tubular spacer 9 having similar means for forming a gas 65 and liquid tight connection with the lower section bosses 4 is inserted therebetween, as shown in Figure 2, forming a means of communication between the bottom of these sections. 75

The float chamber 5 is provided with a float operated valve 10 operated by a float 11 arranged in said chamber, which valve is provided with a connection 12 to the high pressure side of the ice machine compressor 80 and is so constructed that the valve remains open until the liquid refrigerant fills the sides and bottom of the section and its level rises in the float chamber, as indicated by the dotted line on Figure 2, sufficiently to 85 raise the float and close the valve. The float chamber 5 is also provided with a connection 13 to the low pressure side of the compressor, which, during its operation of the ice machine, relieves the pressure above 90 the liquid in the float chamber, whereby the refrigerating liquid is evaporated and passes off therethrough. During evaporation the refrigerant absorbs heat from the surrounding atmosphere which reduces the temperature of the refrigerating or ice compartment of the ice box. The operation of the float 95 11 is the normal operation of the customary float valve in this type and system of ice machine.

This particular construction provides a very simple means for connecting the float valve chamber 5 to the unit at the proper level without increasing the width of the unit to any great extent. Float valve chambers are usually employed for the same purpose as this one in units of this character and are either connected to the side of a section or attached to the side of the refrigerating or ice compartment of the ice 100 105 110

box. The refrigerating units are customarily constructed so as to be received within refrigerating or ice compartments of a standard size ice box with but little space 5 to spare on either side so that it is difficult to install a float chamber of proper dimensions at the side of such a unit. It is to be noted in the present invention that the float chamber boss 6 is only of such width 10 as to provide proper communication between the section bosses and chamber and depends below the float chamber so that the float chamber may be of any desired diameter and the width of the entire unit is only 15 increased by the width of the boss. This particular type of float chamber and means for attaching the same between the sections provides an efficient device readily adapted to standard sections for refrigerating units. 20 As illustrated upon the drawings, the ice cube trays 14 are supported upon the horizontal ribs 15 extending from inner sides of the sections and the tray compartment is closed at the top, bottom and rear by customary continuous plate 16 secured to the front of each section, as shown in Figures 25 1 and 2, and the front of this chamber may be closed, if desired, by a door hinged to the upper edge of said plate in the customary 30 manner.

What I claim is:

1. A refrigerating unit comprising hollow spaced apart side sections for containing the

refrigerating fluid, a tubular spacer interposed between said sections at the bottom 35 and communicating with the interior thereof, a float valve chamber, a tubular boss depending therefrom corresponding in width to said spacer and interposed between said sections at the top and communicating with 40 the interior thereof and with said chamber, a float and float-operated valve within said chamber for controlling the admission of the refrigerating fluid.

2. A refrigerating unit comprising hollow 45 spaced apart side sections for containing the refrigerating fluid having corresponding tubular bosses at the top and bottom of the adjacent sides projecting in line each with the other and communicating with the interior of the respective sections, a float valve chamber, a tubular boss depending therefrom of lesser width than said chamber and interposed between and in communication with the upper aligned side bosses, a tubular 50 spacer similar in width to the valve chamber boss, interposed between and in communication with the interior of the lower aligned side bosses, and a float and float-operated valve within said valve chamber 55 for controlling the admission of the refrigerating fluid.

Signed at Bloomington, Illinois, this 18th day of October, 1927.

ROBERT N. COOPER.
